UNITED STATES PATENT OFFICE.

GEORGE THEOBALD, OF BOSTON, MASSACHUSETTS, ASSIGNOR OF ONE-HALF
TO ADAMS & ILSLEY, OF SAME PLACE.

CHECK-REIN.

SPECIFICATION forming part of Letters Patent No. 268,147, dated November 28, 1882.

Application filed September 30, 1878.

To all whom it may concern:

Be it known that I, GEORGE THEOBALD, residing at Boston, in the county of Suffolk and State of Massachusetts, have invented 5 certain new and useful Improvements in Elastic Connecting Devices for Check-Reins, of which the following is a specification.

This invention relates to elastic connections interposed between the check-rein and saddle-hook; and it consists in a device of peculiar construction, hereinafter described and claimed.

Figure 1 is a plan view, partly in section, of this improved check-rein attachment. Fig. 2 is a perspective view, showing the device in use.

15 A flexible sheath, *e*, composed of leather, is provided at one end with a loop, *f*, integral with the sheath, and partially closed at its opposite end by a centrally-slotted cap, *h*. A metallic rod, *b*, passes through the slot in the cap *h* and 20 slides in the sheath. This rod is provided at its outer end with a loop, *b'*, and at its inner end with a disk or fixed collar, *b''*. A collar, *d*, loose on the rod *a*, rests against the cap *h* of the sheath. A spiral spring, *a*, surrounds 25 the rod within the sheath, one end resting against the fixed collar *b''* and the other end against the loose collar *d*.

The operation is as follows: The check-rein *c* being passed through the loop *b'* and the loop *f* passed over the saddle-hook *k*, when the horse 30 stumbles or falls to the ground the parts yield and prevent the breaking of the check-rein or

saddle-hook, and avoid a painful strain upon or laceration of the mouth of the horse. The device also tends to check the stumble of the 35 horse by its increasing resistance, and to assist him in regaining his feet by its gradual recoil. It also tends to make a pulling horse a tractable and easy driver.

I am aware that elastic connections for check- 40 reins are not new, broadly.

The leather sheath prevents oxidation of the spring, presents a symmetrical appearance with the other portions of the harness, and the flexible loop integral therewith tends to cheapness 45 of production and facility of application, and avoids abrasion of the saddle-hook.

Having thus described my invention, I claim as new and desire to secure by Letters Patent—

An elastic device for connecting the check-rein and saddle-hook, consisting of a flexible tubular leather sheath, partially closed at one end and provided at the other end with a flexible loop integral with the sheath, a metallic rod which slides in the sheath, provided with a 50 fixed collar at its inner end and a loop at its outer end, a collar loose on said rod within the sheath, and a spiral spring surrounding the rod between the fixed and loose collars, substantially as described.

GEORGE THEOBALD.
